REFRACTORY CONSTRUCTION
FOR FURNACES

Harry A. Morlock, Buffalo, N. Y.

Application September 21, 1937, Serial No. 164,898

11 Claims. (Cl. 72—37)

This invention relates to furnace construction and it has particular relation to structure and arrangement of refractory elements employed in building furnaces.

5 One object of the invention is to provide an improved furnace wall construction.

Another object of the invention is to provide an improved compound refractory element for building furnaces.

10 Another object of the invention is to provide an improved combination of refractory element and metal jacket for use as a unit for building either furnace walls or roofs.

In the construction of the refractory parts of 15 metallurgical, smelting and other heating furnaces, it is customary to use refractories of such physically unstable nature that relatively great volume changes may be induced therein as a result of slight changes in temperature. These 20 volume changes impart physical shock to the refractories and at some point along the temperature gradient of the elements of the refractories, which can be in the form of brick or tile, a stress is set up which results in shearing or other form 25 of fracture. As a result, fragments of brick fall from the structure of the furnace and the refractory thickness is reduced. This physical instability is particularly evident in basic refractories, i. e., those containing magnesite (magnesium oxide), lime (calcium oxide) and brick 30 composed wholly of natural iron chromate, otherwise termed chromite or chrome ore, as well as mixtures of these refractories.

It has been found that the spalls resulting from 35 fractured refractories can be retained by placing thin steel plates in the joints between the brick. As a result of heating, these steel plates are converted into iron oxide and tend to flux and combine with a portion of the adjacent refractory 40 wall or surface in such manner as to weld or knit the wall or surface into a unitary structure or monolith. This kind of construction does not prevent fracturing of the refractories, but it does tend to hold any spalls or fragments in place in 45 such manner that effective refractory thickness is maintained.

In the forms of construction previously developed considerable difficulty has been experienced 50 because of excessive crystalline growth which occurs in the iron oxide and refractory combination in the joints between the brick or tiles. In all previously advanced methods of utilizing the advantages of the metal plate joint as a metal jacket in combination with tile it has been necessary to introduce two thicknesses of metal in a

portion of the joint. The excessive amount of metal has caused the formation of an amount of iron oxide in excess of that required to combine with and bond the refractory tile. This excess iron oxide, either alone or in combination with the refractory material during the life of the furnace, undergoes crystalline growth with a great increase in volume. In certain types of furnaces, it is impracticable or impossible to provide for additional dimensions of furnace lining 10 after this growth has occurred. Undesirable features of such growth are exemplified in buckling, shearing and other phases of mechanical failure in the construction.

According to this invention, a practical and 15 superior arrangement of refractory elements has been provided to reduce to a minimum the crystalline growth without relinquishing the desirable features of the combination of the refractory material and metal plates wherein fluxed and 20 welded joints are insured. To this end a tile or brick is provided with a metal jacket or container covering approximately one half of the brick length on the four sides thereof so that in each joint between each adjacent brick or tile only 25 one thickness of metal is obtained and the crystalline growth thus reduced. Thus the cost of metal is reduced approximately to one-half that necessary when two thicknesses of metal were used.

In order to expedite and otherwise facilitate 30 commercial availability of the refractory product the jackets are permanently applied to the bricks at the manufacturing plant. Each brick, with 35 its metal jacket thereon, can then be handled and transported without danger of displacement of the jacket, and this desirable condition continues during the handling of the refractories incidental to the actual installation of the furnace walls. A practical and efficient method of 40 securing the metal jacket to the brick includes the forming of a notch or groove in one or more sides of the brick and pressing a rib or flange from the side portion or portions of the jacket into the groove. The side or body of the jacket 45 can be slit for purposes of facilitating the forcing of the flange or rib into the groove.

The advantages of this type of construction can be extended to various types of brick or tile refractories, such as the key, wedge, etc., by forming the jacket to conform to the shape of the end portion of the brick to which it is applied.

In building the furnace wall or roof the bricks are laid in such manner that the metal covered portions are alternately arranged, that is, the 55

metal covered portion of one brick abuts or lies adjacent the uncovered portion of the adjacent bricks. This formation is equally applicable to the key or wedge form, in which the larger end 5 of one brick is provided with a metal jacket and the smaller end of the next adjacent brick is provided with a like jacket. Thus the joints between the bricks are provided with a substantially continuous single thickness of metal and 10 during use of the furnace a fluxing and binding of the metal surfaces to the brick surfaces occurs by reason of the oxidizing action of the metal.

In the drawing:

Fig. 1 is a fragmentary elevation of a furnace 15 in which portions of the outer furnace wall have been removed to expose the arrangement of the refractory tile or brick;

Fig. 2 is a perspective, on a larger scale, of a refractory element provided with a partial cover 20 or jacket; and

Fig. 3 is a perspective, on a larger scale, of refractory elements of another form.

In practicing the invention a conventional furnace 10 is provided with an outer wall structure 12 composed of refractory tile or brick 15, and a roof 16 composed of refractory tile or brick 17. The furnace is also provided with conventional skew back structure 18 and other reinforcing and covering 19.

As best shown in Fig. 2, one form of tile or brick 15 is oblong and is provided with plain rectangular sides 22 running lengthwise thereof. A metal jacket 23 covers approximately one-half 25 of the length of each of the longer sides 22 of the brick. In order to insure proper assembly of the brick and jacket one or more sides of the brick is provided with a transverse groove or recess 25 into which a pressed out portion 26 from the body of the metal jacket is pressed or otherwise forced. Thus the brick and jacket are firmly secured together and can be handled as a unit 40 brick and transported without danger of disassembly. If desirable, the body of the jacket can be slit, as indicated at 27, and the pressed out portion 26 can be in the form of a flange, or if the slit is omitted, the pressed out portion can be in the form of a bead or rib.

In building the furnace wall structure 12, the bricks 15 are alternately placed in such manner 50 that the jacketed portion of each brick rests in contact with the bare or unjacketed portion of an adjacent brick. Hence, throughout the furnace wall structure, substantially uniform single thickness of metal covers all of the contiguous 55 sides of the bricks that would otherwise be exposed to each other directly if the jackets were not used.

It is to be understood that the definition of sides as applied to each building block is intended in this description to refer to those sides 60 22 which are laid in face to face relation to sides of adjacent blocks and extend transversely of the wall in a furnace construction. The ends of the block are those extremities which are substantially parallel to the face of the furnace wall construction, or form the wall facing. Each side 22 (Fig. 2) has a metal covered portion and an uncovered portion as clearly indicated. It should be noted that the uncovered portion of each 70 side has a definite relation to an opposed metal covered complementary side portion, or counterpart thereof, but not necessarily of the same area. Each metal covered side portion extending toward one end of the block is thus substantially complementary, or is opposed in symmetrical re-

lation, to an opposed uncovered side portion on the opposite block side, but extending toward the other end of the block. Each metal covered side portion is likewise substantially complementary to an uncovered side portion of an adjacent block in the furnace wall or roof construction and vice versa. Therefore, in fitting composite masonry units together in a wall construction, each uncovered side portion of one block is capable of fitting in face to face or opposed relation 10 to a complementary metal covered side portion of an adjacent composite unit. In such wall construction, it is to be understood that the matter of whether the blocks might be shorter transversely of the wall than the extent of the blocks 15 along the wall face does not materially affect the application of the principles of the invention.

Approximately the same kind of arrangement is included in the roof 16, in which the several bricks 17 are tapered and constitute the so-called wedge type. Suitable jackets 20 are applied to the bricks in the same manner as that previously described with the exception that the jackets on alternate bricks must be made to conform to wedge like shape, and since each brick 25 tapers, a larger jacket is placed on the larger brick end and a smaller jacket is placed on the smaller brick end. In this arrangement, both the smaller and the larger jackets are placed on the bricks by inserting the smaller end of the 30 latter therein, and thus a single thickness of metal separates the brick in the roof structure. There are also provided suitable notches or grooves 22 and pressed out portions 33 similar to the grooves 25 and pressed out portions 26 of 35 the form of arrangement shown in Fig. 2.

In Fig. 3, the so-called key type of bricks is shown and in this form, each brick is tapered somewhat differently from the brick 17 of the roof, but since each roof brick, with its jacket 40 is generally similar in construction and arrangement to that shown in this figure, similar reference characters are employed to designate corresponding elements.

Although only the preferred forms of the invention have been shown and described in detail, it will be apparent to those skilled in the art that the invention is not so limited, but that various changes can be made therein without departing from the spirit of the invention or 50 from the scope of the appended claims.

I claim:

1. In a furnace construction, a wall section including a series of refractory building blocks, each block from its medial portion toward one extremity having a metal jacket completely surrounding it and providing an uncovered portion toward the opposite extremity, the metal surrounded portion of each block being laid adjacent the uncovered portion of an adjacent block 60 whereby a substantially continuous single thickness of metal is provided in the joints between the blocks.

2. In a furnace construction, a roof section including a series of tapered refractory building blocks, successive blocks having metal jackets surrounding alternately the larger and smaller block end portions and leaving alternate uncovered larger and smaller block end portions whereby a substantially continuous single thickness of metal is provided in the joints between the several blocks.

3. In a furnace construction, a wall section including a series of refractory building blocks, each block from its medial portion toward one 75

- extremity having a metal jacket completely surrounding it and providing an uncovered portion toward the opposite extremity, the metal surrounded portion of each block being laid adjacent the uncovered portion of an adjacent block whereby a substantially continuous single thickness of metal is provided in the joints between the blocks, each block having a groove formed therein, and each metal jacket having a pressed out portion disposed in the groove of its block. 5
4. In a furnace construction, a roof section including a series of tapered refractory building blocks, successive blocks having metal jackets surrounding alternately the larger and smaller block end portions and leaving alternate uncovered larger and smaller block end portions whereby a substantially continuous single thickness of metal is provided in the joints between the several blocks, each block having a groove formed in the metal surrounded portion thereof, and each metal jacket having a pressed out rib portion disposed in the groove of its block. 10
5. In a masonry section of a furnace structure, a plurality of refractory building blocks, each block forming joints with adjacent blocks, covering of metallic sheet material applied to side portions of a plurality of said blocks, a plurality of side portions of a plurality of said blocks being free from metallic covering, the covering of metallic sheet material being placed against uncovered side portions of adjacent blocks whereby a substantially single thickness of metallic sheet material is provided in the joints of the masonry section. 15
6. In a furnace construction, a plurality of contiguous refractory building blocks, covering of metallic sheet material applied to a plurality of sides of each block, edges of the metallic sheet material on one block fitting in opposed relation to adjacent edges of metallic sheet material of other blocks, each block having uncovered side portions fitting against sides of the metallic sheet material on other blocks whereby a substantially continuous single thickness of metallic sheet material is disposed in the joints formed by the blocks. 20
7. In a furnace construction, a refractory building block, covering of metallic sheet material applied to a plurality of sides of said block, a second refractory building block having metallic sheet material applied to a plurality of its sides in symmetric relation to the covering on the first mentioned block, a side portion of the first mentioned block being free from metallic covering and contacting directly against a side of the metallic sheet material applied to the second block, whereby the portions of sheet material disposed between the blocks are in a common plane and constitute a substantially single thickness of metallic material between said blocks. 25
8. A masonry unit comprising a refractory block, a metallic band perimetricaly embracing a portion of said block, the remaining portion of said block extending beyond said band. 15
9. A masonry unit comprising a refractory block, a metallic band perimetricaly embracing a portion of said block and interlocked therewith, the remaining portion of said block extending beyond said band. 20
10. A masonry unit comprising a refractory block, a metallic band perimetricaly embracing approximately one-half of said block, the remaining portion of said block extending beyond said band. 25
11. A furnace constructing masonry unit adapted to be installed in a furnace construction with other like units comprising a refractory building block, a metallic covering disposed upon a plurality of side portions of said block, approximately one-half of the sum of the total side areas of said refractory block being normally metal covered and uncovered, respectively, the uncovered side portions and metal covered side portions being disposed in substantially opposed symmetrical relation, each uncovered side portion being substantially complementary to a metal covered side portion of said block and capable of receiving in face to face relation a metal covered side portion of a like refractory block. 30
